CLOCK

Charles A. McLeod, Chicago, Ill., assignor to Sunbeam Corporation, Chicago, Ill., a corporation of Illinois

Filed Aug. 4, 1967, Ser. No. 8,134

Term of patent 14 years

(Cl. D42—7)

Fig. 4.

Fig. 5.

FIG. 1 is a front elevational view of a clock embodying my new design;

FIG. 2 is a top plan view thereof;

FIG. 3 is a sectional view taken substantially along line 3—3 of FIG. 1;

FIG. 4 is a perspective view thereof; and

FIG. 5 is a fragmentary sectional view taken substantially along line 5—5 of FIG. 1.

The dominant features of the design are shown in solid lines and reside primarily in the inward taper of the case from front to rear in combination with the concave face.

I claim:

The ornamental design for a clock, as shown and described.
